(57) **CLAIM**

The ornamental design for an extramedullary modular post, as shown and described.

DESCRIPTION

FIG. 1 is a perspective view of an extramedullary modular post shown in an environment illustrating our new design; FIG. 2 is a right side elevation view of the extramedullary modular post shown removed from its environment in order to show aspects of the design that are not apparent in the perspective view;

FIG. 3 is a left side elevation view thereof;

FIG. 4 is a rear end elevation view thereof;

FIG. 5 is a front end elevation view thereof;

FIG. 6 is a top plan view thereof;

FIG. 7 is a bottom plan view thereof; and,

FIG. 8 is perspective view thereof.

The evenly spaced broken lines shown that are immediately adjacent the shaded areas, and define unshaded regions, represent unclaimed boundaries while the remaining evenly spaced broken lines and the dot-dash broken lines are directed to environment and are for illustrative purposes only; the broken lines form no part of the claimed design.
